(57) CLAIM

The ornamental design for a handshower as shown and described.

DESCRIPTION

FIG. 1 is a perspective view of a handshower, showing our new design;

FIG. 2 is a front view thereof;

FIG. 3 is a rear view thereof;

FIG. 4 is a side view thereof;

FIG. 5 is another side view thereof;

FIG. 6 is a top view thereof; and,

FIG. 7 is a bottom view thereof.

Equal length dash-dash broken lines illustrate portions of the handshower that form no part of the claimed design. Dash-dot-dash broken lines illustrate boundaries and form no part of the claimed design.

1 Claim, 7 Drawing Sheets
